UNITED STATES PATENT OFFICE.

GLENN D. MORRISON, OF CANONSBURG, PENNSYLVANIA, ASSIGNOR TO CONTINENTAL CAN COMPANY, INC., OF NEW YORK, N. Y., A CORPORATION OF NEW YORK.

MACHINE FOR DOUBLING METAL PLATES.

Application filed February 25, 1927. Serial No. 170,861.

The invention relates to new and useful improvements in machines for doubling metal plates. Machines of this character have been constructed wherein the sheets 5 to be doubled are laid in horizontal position on a bed and then are raised to vertical position for doubling, and before the doubling mechanism operates upon the sheets, matching levers or arms engage the ends of the 10 sheets and position the same with their edges even and centrally disposed relative to the doubling mechanism. This means for raising the sheets is operated independently of the doubling mechanism and is actuated by a 15 manually controlled clutch. After these devices have performed their function of raising and evening the sheets, then they are released from the actuating mechanism and returned to their initial position for receiving other sheets.

An object of the present invention is to provide a means for retarding the return of these parts to their initial position when they are released from the actuating mechanism therefor.

In the drawings which show by way of illustration one embodiment of the invention—

Figure 1 is a side view of a doubling machine embodying the improvement;

Fig. 2 is an end view of a part of the machine taken from the left-hand as viewed in Fig. 1;

Fig. 3 is a view showing on an enlarged scale, and more or less diagrammatically, the means for raising the arms which lift the sheets and the retarding means therefor, and

Fig. 4 is a detail in plan showing the treadle-controlled bell crank for shifting the clutch.

The doubling machine consists of a frame which is provided with a bed 1 and an upright supporting part 2. The sheets to be folded are laid on the bed in horizontal position. A plurality of sheets are usually folded at the same time, and in Fig. 1, the sheets are indicated at S. After the sheets have been placed, they are raised to a vertical position as indicated by the broken lines in Fig. 1 at S'. This is accomplished by the swinging arms 3, 3. There is a pair of arms, one at each side of the center of the sheet, so that the doubling mechanism may operate

at the center of the sheet. This doubling machine is of the type shown in the patent granted Steele July 14, 1925, No. 1,546,039, and detail description of the doubling mechanism is not thought necessary.

Only one of the matching or evening levers is shown in the drawings, as these devices are similar in construction to those shown in the Steele patent. The matching lever or arm includes a member 4. This member is pivoted at 5 to a cross beam 6 carried by the upright portion 2 of the machine. Rigid with the support for the member 4 is an arm 7.

This support also carries an arm 8, and a link 9 joins the arm 8 with a similar arm 70 on the supporting member for the other matching lever. This causes the two matching levers to work at the same time, but of course, in opposite directions. That is, they are moved in to engage the ends of the sheet 75 and then are moved away from the ends of the sheet. A spring 10 attached to the arm 7 and the frame of the machine normally holds the matching lever in raised position. The matching lever is provided on the end 80 thereof with an arm 11 which engages the ends of the sheets. This arm is pivoted on the end of the matching lever and is adjustably connected to a bracket 12 which in turn is connected to a link 13 pivoted at 14 85 to a lug 15 on the frame. These features form no part of the present invention, and further description thereof is not thought necessary. The matching levers are lowered by means of a chain or other flexible member 90 16 which is connected at 17 to the outer end of the arm 7. A downward pull on this chain will cause the matching levers to move downwardly against the tension of the spring 10 and engage the ends of the sheet. Both matching levers are moved downwardly at the same time, and they will engage the opposite ends of the sheet, even the ends of the sheet and place the sheet centrally on the bed for the action of the doubling mechanism.

The matching levers are held in raised position until after the lifting arms have raised the sheet to vertical position. This is accomplished by means of a latch 18. The latch 18 is pivoted at 19 to the beam 6, and is provided with a finger 20 which is adapted to engage a shoulder 21 on the arm 7. There

is a weight 22 attached to the lower end of the latch operating member 18, and this normally holds the latch in position to engage the shoulder on the arm 7, and when so positioned, it will hold the arm raised against any downward pull on the chain 16. A link 23 is connected to this latch operating member 18 at its upper end, and this link is pivoted at 24 to a lever arm 25, which is pivotally supported on a bracket 26. If the free end 27 of this lever arm 25 is engaged and raised, it will pull down on the link 23 and thus move the member 20 away from the shoulder 21 and permit the actuation of the arm 7.

The lifting arms 3 are pivoted at 28 to the bed of the machine. The lifting arm has an extension 29 beyond the pivot 28, to which the link 30 is connected. The link 30 is pivoted at 31 to an arm 32 fixed to a shaft 33. There is, of course, an arm 32, and similar connecting mechanism for each lifting arm. On the outer end of the shaft 33 there is an actuating arm 34. This actuating arm 34 is provided with an idler pulley 35. The chain 16 runs over this idler pulley, and when the chain is drawn upon, it will raise the arm 34, and this in turn will cause the lifting arms 3 to be raised to vertical position. The end of the arm 34 is provided with a projecting lug 36. The end 27 of the lever arm 25 lies in the path of movement of the end of the arm 34, as clearly shown in Fig. 3. It is the end of the arm 34 which engages this member 27, and the lug 36 insures that the member 27 will not slip off from the end of the arm 34.

It will be apparent that when the chain 16 is pulled upon, the first member to be actuated will be the arm 34, as the arm 7 is locked in raised position. This arm 34 is raised to the position shown in Fig. 3, which has caused the arms 3 to be lifted to vertical position, and then the member 27 is engaged, which releases the latch holding the arm 7 raised, and further pull on the chain 16 will then operate the matching levers.

The chain 16 is connected to a chain drum 37 mounted on a sleeve which in turn is freely mounted on an actuating shaft 38. On this sleeve is a brake drum 39. A clutch 40 of any desired construction may be used for connecting the sleeve carrying the drum 37 to the actuating shaft 38. The clutch 40 is shifted by means of manually operated devices. These manually operated devices include a lever 41 which is pivoted at 42. This lever operates upon a fork 43 which shifts the clutch parts to either connect or disconnect the actuating shaft with the drum 37 which operates upon the chain. When the drum 37 is rotated, then the chain will be wound on the drum, the arm 34 raised, lifting the arms 3 and then operating

the matching levers. When the clutch is released, then the drum 37 is freed from the actuating shaft, and will turn so as to give up the chain and permit the parts to return to their initial position. The spring 10 will raise the matching levers, and gravity is sufficient to return the arm 34 and the arms 3, 3 to their initial horizontal position.

This return of the arms 3, 3 by gravity, is retarded, and it is this retarding means for easing the return movement of the actuated parts just described that form the principal part of the present invention. This as illustrated in the drawings, is accomplished by means of a brake shoe 44. The brake shoe 44 is carried by a lever pivoted at 45 on a bracket 46. A rod 47 passes through the end 48 of the lever carrying the brake shoe 44. A spring 49 bears against the upper face of the end 48 of the lever carrying the brake shoe, and also against a wing nut 50. By turning the wing nut, the tension of the spring can be varied. This spring forces the brake shoe into contact with the drum 39 and retards the movement of the drum. This braking of the drum 39 is continuous. It does not need to be excessive in order to ease the return movement of the parts actuated by the drum 39, and therefore, the brake is continuously applied to the drum, according to the present invention. This, however, is not material. The essential feature is that the brake shall be applied to the drum 39, or some part movable with the drum 37 on which the chain is wound during return movement of arm 3.

The clutch lever 41 is oscillated by means of a bell crank 51. This bell crank 51 is pivoted at 52 to the frame of the machine, and is provided with an arm to which a link 53 is connected. This link 53 is in turn pivoted to an arm 54 pivoted at 55 in a bracket 56. There is a second arm 57 which is rigid with the arm 54, and a plunger 58 movable vertically in suitable bearings therefor, engages the end of the arm 57. When this plunger is depressed by the operator stepping on the foot plate 59 at the upper end of the plunger 58, it will actuate the arm 54 so as to pull on the link 53. This in turn will swing the bell crank 51 so as to move the lower end of the lever 41 toward the center of the machine. This will move the upper end of the lever away from the center of the machine. The upper end of the lever is connected to the fork 43 which is pivoted at 60 to the bracket support therefor, and this will close the clutch. The operator, therefore, stepping on the foot plate 59 through the parts mentioned, will cause the actuating shaft to be connected to the chain drum, and the drum turned in a counterclockwise direction as viewed in Fig. 3. This winding up of the chain will lift the arm 34, thus raising the arms 3, 3 to vertical position, and this sets

the stack of sheets on edge. When the arm 34 engages the end 27 of the trip control for the matching levers, then the matching levers will be released, and the further winding up of the chain will actuate the matching levers. As soon as the sheets have been properly matched and centered, then the operator releases the foot plate 59 and the spring 61 engaging the upper end of the clutch shifting lever 41, will pull on the upper end of the lever and disengage the clutch members. When the clutch members are disengaged, then the drum which winds up the chain is free to rotate in a clockwise direction, except for the retarding of its movements through the action of the brake shoe 44. The pressure of the brake shoe can be adjusted so as to put just sufficient braking on the free running of the chain drum to retard the movement of the arms 3, 3 as they return to their initial position. This prevents the arms from dropping suddenly and breaking.

The foot treadle or plate 62 is for controlling the doubling mechanism, and therefore, after the plates have been properly positioned, the operator stepping upon the foot plate 62 will cause the doubling mechanism to be actuated. This mechanism, as above noted, forms no part of the present invention and has not been shown.

It is obvious that minor changes in the details of construction and the arrangement of the parts may be made without departing from the spirit of the invention as set forth in the appended claims.

Having thus described the invention, what I claim as new and desire to secure by Letters Patent, is—

1. A machine for doubling metal sheets including in combination, a supporting bed, lifting arms adapted to receive the sheets in horizontal position and for raising said sheets to vertical position, manually controlled means for raising said arms to vertical position including an actuating shaft, a clutch for connecting said shaft to the means for lifting the arms, manually operated devices for shifting and releasing the clutch, and means for retarding the return movement of the arms when released from the actuating mechanism therefor.

2. A machine for doubling metal sheets including in combination, a supporting bed, lifting arms adapted to receive the sheets in horizontal position and for raising said sheets to vertical position, manually controlled means for raising said arms to vertical position including an actuating shaft, a clutch for connecting said shaft to the means for lifting the arms, manually operated devices for shifting and releasing the clutch, and means for retarding the return movement of the arms when released from the actuating mechanism therefor, said means

for retarding the return movement of the arms including a brake drum and a brake shoe adapted to engage said brake drum.

3. A machine for doubling metal sheets including in combination, a supporting bed, lifting arms adapted to receive the sheets in horizontal position and for raising said sheets to vertical position, manually controlled means for raising said arms to vertical position including an actuating shaft, a clutch for connecting said shaft to the means for lifting the arms, manually operated devices for shifting and releasing the clutch, means for retarding the return movement of the arms when released from the actuating mechanism therefor, said means for retarding the return movement of the arms including a brake drum and a brake shoe adapted to engage said brake drum, and an adjustable tension means for continuously pressing said brake shoe against said drum.

4. A machine for doubling metal sheets including a bed, lifting arms for receiving said sheets in horizontal position and movable to vertical position for raising the sheets, devices for raising said lifting arms, matching levers for engaging the ends of the sheets for positioning the sheets on the bed, an actuating shaft, a chain drum freely mounted on said shaft, a chain running over said drum and connected to said devices for raising the arms and for actuating said matching levers, a manually controlled clutch for connecting said chain drum to said actuating shaft, and means for retarding the movement of said chain drum when released from said actuating shaft for retarding the return movements of said arms and matching levers to initial position.

5. A machine for doubling metal sheets including a bed, lifting arms for receiving said sheets in horizontal position and movable to vertical position for raising the sheets, matching levers for engaging the ends of the sheets for positioning the sheets on the bed, an actuating shaft, devices for raising said arms, a chain drum freely mounted on said shaft, a chain running over said drum and connected to said devices for raising the arms and for actuating said matching levers, a manually controlled clutch for connecting said chain drum to said actuating shaft, and means for retarding the movement of said chain drum when released from said actuating shaft for retarding the return movements of said arms and matching levers to initial position, said retarding means including a brake drum connected to said chain drum, and a brake shoe adapted to bear against said brake drum.

6. A machine for doubling metal sheets including a bed, lifting arms for receiving said sheets in horizontal position and movable to vertical position for raising the sheets, matching levers for engaging the ends

of the sheets for positioning the sheets on the bed, an actuating shaft, devices for raising said arms, a chain drum freely mounted on said shaft, a chain running over said drum and connected to said devices for raising the arms and for actuating said matching levers, a manually controlled clutch for connecting said chain drum to said actuating shaft, means for retarding the movement of said chain drum when released from said

actuating shaft for retarding the return movements of said arms and matching levers to initial position, said retarding means including a brake drum connected to said chain drum, a brake shoe adapted to bear against said brake drum, and adjustable tension means for continuously pressing said brake shoe against said brake drum. 15

In testimony whereof, I affix my signature.
GLENN D. MORRISON.
